VALVE KEEPER TOOL

Claude W. Vandament, P.O. Box 261, Hedrick, Iowa

Filed May 14, 1958, Ser. No. 735,184

1 Claim. (Cl. 81—5.1)

My invention relates to tools and more particularly to a tool used in the mounting of valves in internal combustion engines.

Some internal combustion engines do not have overhead valve systems. Many times, the valves are located in the lower portion of the motor block and are inclined at various angles. Most of these engines known to me utilize a conventional valve mechanism which has a seating portion, a stem and a spring means on the stem to assist in the operation of the valve. The above mentioned spring means is generally held in compression between the motor block and a cup element on the valve stem. The cup element on the valve stem is generally secured to the valve stem by two semi-circular valve keepers. These keepers embrace the valve stem and fit into grooves in the stem to stand in the path of the cup as the spring attempts to force the cup past the keepers. When the valves are located on an inaccessible part of the motor, the handling of these valve keepers becomes very tedious. My invention directly relates to a tool which overcomes the difficulty in handling these valve keepers.

Heretofore, these valve keepers have been installed by hand. The small size of the keepers combined with the lack of operating space invite dropping of the keepers. Furthermore, the two keepers must both be installed to effectively hold the valve cup and the manual installation of the keepers therefore requires that one keeper be manually held in place while the other keeper is being installed. Space requirements make this almost impossible and many times grease or the like is placed on the first keeper to hold it in place until the other keeper is installed.

Therefore, the principal object of my invention is to provide a valve keeper tool that will permit absolute control over the valve keepers at all times during the valve installation operation.

A further object of my invention is to provide a valve keeper tool that can simultaneously place the valve keepers in contact with the valve stem.

A still further object of my invention is to provide a valve keeper tool that can be easily operated and which requires little manual exertion.

A still further object of my invention is to provide a valve keeper tool that can hold and retain the valve keepers while the tool is being moved into operating position.

A still further object of my invention is to provide a valve keeper tool that is economical of manufacture, durable in use and refined in appearance.

These and other objects will be apparent to those skilled in the art.

My invention consists in the construction, arrangements, and combination, of the various parts of the device, whereby the objects contemplated are attained as hereinafter more fully set forth, specifically pointed out

2

in my claim, and illustrated in the accompanying drawings, in which:

Fig. 1 is a perspective view of my device in its opened position;

5 Fig. 2 is a perspective view of my device in its closed position and shows the tool holding the valve keepers in engagement with a valve stem.

Fig. 3 is a partial sectional view taken along the longitudinal axis of my device when my device is in the position shown in Fig. 2. Fig. 3 also shows the details of the valve structure upon which the valve keepers are being mounted; and

10 Fig. 4 is a partial plan view of the forward end of my device as it moves the valve keepers into engagement with the valve stem.

I have used the numeral 10 to designate the block of an internal combustion engine with a valve-receiving well opening 12. The bottom of well 12 has a round hole opening 14 capable of receiving the vertical stem 16 of valve 18. The lower end of valve stem 16 has two parallel, horizontal grooves 20 and 22. Valve keepers 24 and 26 each have interior beads 28 and 30 which are adapted to enter into the grooves 20 and 22, respectively, of valve stem 16 when the keepers embrace the stem. 15 It will be noted that the outside surfaces of the two keepers 24 and 26 form a conical surface which tapers upwardly and inwardly. A cup member 32 with outer flange 34 has a circular center hole 35 about which interior cone-shaped portion 36 extends. Cup member 32 is adapted to receive valve stem 16 through center hole 35 and cone portion 36 is adapted to embrace the outer surfaces of valve keepers 24 and 26. A spring 38 extends around valve stem 16 and has its upper and lower ends in engagement with block 10 and the flange 34 20 on cup member 32, respectively. Spring 38 ordinarily forces cup member 32 into engagement with valve keepers 24 and 26. Spring 38 is shown to be slightly compressed in Fig. 3 and this can be accomplished by clamping a valve lifter tool on the top of block 10 and the bottom of cup member 32. This valve lifter tool has not been shown. The above described structure is typical of many internal combustion engines and does not comprise a part of my invention.

My tool is comprised of two handles 40 and 42 which are substantially identical and differ only enough to form a symmetrical appearance when placed opposite each other. The rear ends of handles 40 and 42 are curved outwardly from each other to form gripping areas 44 and 46, respectively. The forward ends of gripping areas 44 and 46 terminate in straight portions 48 and 50, respectively. Portions 48 and 50 are bent slightly downwardly at 52 (see Fig. 3) and the forward ends of handles 40 and 42 terminate in arcuate portions 54 and 56, respectively. The arcuate portions 54 and 56 each have 25 a flange 58 on their lower edges. Flange 58 is of substantial uniform width and coincides with the shape of the arcuate portions 54 and 56. I prefer to have the arcuate portions 54 and 56 along with flanges 58 magnetized.

30 Ears 60 and 62 extend laterally inwardly from the straight portions 48 and 50, respectively, of handle members 40 and 42. These ears 60 and 62 are adapted to overlap and center holes 64 in the ears are permitted to register. The ears are then pivotally connected by 35 a rivet 66 which extends in a vertical position through the holes 64.

A lug 68 appears on the inward face of each handle 40 and 42 rearwardly of rivet 66. A spring 70, which is normally in its expanded condition, embraces lugs 68 and normally forces the gripping areas 44 and 46 apart, and forces the arcuate portions 54 and 56 together. It

should be noted that the size and shape of arcuate portions 54 and 56 define less than a perfect circle when forced together. Furthermore, the inner surface as of arcuate portions 54 and 56 are tapered upwardly and inwardly to coincide with the outer surfaces of valve keepers 24 and 26.

A bearing member 72 can be welded to the lower end of rivet 66 with its longitudinal axis extending laterally from handles 40 and 42. A bracket 74 is pivotally mounted in bearing member 72 and is comprised of an arm 75 which extends rearwardly from the pivotal connection, a vertical portion 76 which extends upwardly from the rearward end of arm 75, a crossbar 78 which is horizontally mounted on the top of portion 76, and downwardly extending portions 80 and 82 which are secured to the ends of crossbar 78. As shown in Fig. 1, portions 80 and 82 are adapted to engage handles 40 and 42, respectively, at times to hold spring 70 in compression and to hold arcuate portions 54 and 56 in spaced apart relation.

The normal operation of my device is as follows: When it is desired to place the valve keepers 24 and 26 on valve stem 16, a valve lifter (not shown) is utilized to hold spring 38 and cup member 32 in the position shown in Fig. 3. This valve lifter must be used no matter how the valve keepers are to be installed. The handles 40 and 42 of my device are moved inwardly to compress spring 70 and bracket 74 automatically pivots downwardly so that its downwardly extending portions 80 and 82 engage the outside edges of the respective handle members so that this position of the handle members can be maintained. As indicated above, the compression of spring 70 forces the arcuate portions 54 and 56 into spaced apart relation. The keeper 24 is then placed within the arcuate portion 54 to rest on flange 58 and keeper 26 is similarly placed in arcuate portion 56. Since keepers 24 and 26 are always of metal construction, the magnetism of the arcuate portions will hold the keepers therein.

The tool is then moved so that the lower end of valve stem 16 appears between the arcuate portions 54 and 56. The arm 75 on bracket 74 is then moved manually upwardly to disengage portions 80 and 82 from the handle members. The spring 70 then expands and forces the keeper-carrying arcuate portions 54 and 56 to close on valve stem 16 as shown in Figs. 2, 3 and 4.

The valve lifter can then be operated to lower cup 32 downwardly onto the tool and keepers as shown by the arrows in Fig. 3. Since the handles 40 and 42 are slightly bent at 52, it is possible for the tool to extend

slightly upwardly into cup member 32 without disaligning the keepers with valve stem 16. If the beads 28 and 30 in keepers 24 and 26 have not yet engaged the grooves 20 and 22, respectively, of stem 16, the downward movement of cup 32 will slide the tool and keepers downwardly so that this engagement can be effected. It should be noted that the sliding of the tool does not affect its grip on the valve keepers because of the tapered surface on the inside of the tool's arcuate portions 54 and 56. When the beads of the keepers are in engagement with the grooves of the valve stem, the downward movement of the cup member 32 progressively brings the upper portion of keepers 24 and 26 into engagement with the tapered interior portion 36 of the cup, and shears the tool from its grip on the keepers. Thus, the arcuate portions 54 and 56 progressively yield their control over the keepers 24 and 26 to the interior portion 36 of cup member 32. The full engagement of the cup member 32 with the keepers 24 and 26 will terminate the downward movement of the cup member and the valve will then be installed.

From the foregoing, it is seen that my invention will accomplish at least all of its stated objectives.

Some changes may be made in the construction and arrangement of my valve keeper tool without departing from the real spirit and purpose of my invention, and it is my intention to cover by my claim, any modified forms of structure or use of mechanical equivalents which may be reasonably included within their scope.

I claim:

In a valve keeper tool, a pair of levers in substantial parallelism, handles and jaws on opposite ends of said levers, a pivoted connection between the levers so that the jaws may be spread upon a manual squeezing of the handles, a spring connecting the handles and biasing the handles apart, a bracket pivotally secured to said pivotal connection between the levers and extending toward said spring, and means on said bracket to selectively hold said handles in a position wherein the spring is under compression and the jaws are spread apart.
